SYRINGE ASSEMBLY

Frank E. Brown, Burbank, Calif., assignor to
Frederick M. Turnbull, Los Angeles, Calif.

Application March 16, 1954, Serial No. 416,606

1 Claim. (Cl. 128—218)

This invention relates to a structurally and functionally improved syringe assembly of the hypodermic type.

It is an object of the invention to furnish a readily operable mechanism which may preferably have a "one-time" use, although its parts can be cleaned and sterilized so that it can again be used in subsequent injections.

An additional object is that of furnishing a syringe which will include relatively few units, each individually rugged and simple in design, such units being capable of ready manufacture and assemblage to furnish a mechanism which may be stored in filled condition for indefinite periods of time without the stability of the medicament being affected.

With these and other objects in mind, reference is had to the attached sheet of drawings illustrating practical embodiments of the invention and in which:

Fig. 1 is a sectional side view of a hypodermic syringe assembly;

Fig. 2 is a similar view taken along the line 2—2 in the direction of the arrows as indicated in Fig. 1;

Figs. 3 and 4 are transverse sectional views taken along the lines 3—3 and 4—4, respectively, in the direction of the arrows as also indicated in Fig. 1;

Fig. 5 shows a sectional side view of an alternative form of apparatus with the parts arranged in an initial or inoperative condition;

Fig. 6 is a transverse sectional view taken along the line 6—6 in the direction of the arrows as indicated in Fig. 5;

Fig. 7 is a view similar to Fig. 5 but illustrating the parts in shifted condition, such that they are ready to perform an injection;

Fig. 8 is a further sectional side view of an alternative form of apparatus, and

Fig. 9 is a transverse sectional view taken along the line 9—9 in the direction of the arrows as indicated in Fig. 8.

Referring primarily to Figs. 1 to 4, the numeral 10 indicates a tube or barrel formed of any suitable material such as glass and provided adjacent its opposite ends with flanges 11 and 12. As shown especially in Figs. 3 and 4, these flanges are interrupted throughout certain portions of the circumference of the barrel so that at diametrically opposite points the flanges are, in fact, reduced or non-existent, while at intervening points they provide outstanding ears or mounting portions. Adjacent the rear end of the barrel a plunger is provided in the form of a piston 13 which may be shifted lengthwise of the barrel bore to express the medicament therefrom. At its opposite or outer end the barrel mounts a closure member 14 which provides a perforable diaphragm portion 15 and maintains the medicament against escape. Conveniently the plunger or piston 13 and the closure member 14 are formed of rubber of natural or synthetic types.

A needle 16 is included in the assembly and has its opposite ends pointed. This needle is suitably secured

2

against movement with respect to a cap 17. This cap may be formed of metal or plastic. It is retained in position by having rearwardly and inwardly extending portions 18 in engagement with the outer edges and inner faces of flange 12. It may obviously be applied to that flange by bringing these into general alignment with the interruptions of the flange. Thereafter it is shifted axially towards barrel 10 so that the parts 18 overlap the plane of flange 12. Thereupon, by effecting relative rotation of this cap with respect to the barrel, parts 18 will lie in the positions shown in Figs. 1 and 4 to prevent an accidental separation of the elements.

Similarly an actuator for the plunger is conveniently provided by employing a cap 19 which has forwardly and inwardly extending parts 20 to overlap the flange portions 11. This cap slidably mounts a plunger 21, the diameter of which is sufficiently reduced so that it may enter the bore of barrel 10. At its outer end, plunger 21 may terminate in an actuating or thumb-engaging portion 22. It may also be provided with a bore 23. This bore is capable of receiving the needle prior to the assembly of the parts. So housed the needle will be completely enclosed and protected against contamination. As is apparent, the actuator may be coupled to or detached from the rear end of the barrel by simply moving the parts in an axial direction and rotating the cap 19 with respect to the barrel so as to cause the retaining portions 20 to clear or engage with flange 11.

It will be obvious that the parts of the assembly as shown in Figs. 1 to 4 may be cleaned and sterilized. The bore of barrel 10 is filled with a medicament solution and closed by elements 13 and 14. The plunger 21 conveniently houses the outer end of needle 16 although this is a matter of choice. In any event, when it is desired to use the apparatus, the cap 19 of the actuator assembly is attached to the rear end of the barrel. Cap 17 is coupled to the opposite barrel end. As it is so coupled the inner end of the needle 16 perforates diaphragm portion 15 to establish communication between the interior of the barrel and the bore of the needle. Thus, the barrel provides an external circumferential groove which embraces its outer surface between flanges 11 and 12 and which groove extends through to the end portions as defined by these flanges. The closure member 14 insures against contamination of the medicament under all circumstances prior to the mounting of the needle assembly. The cap 17 furnishes a connector member, the inner surface of which provides a retaining means which engages the outer end of closure or stopper member 14. The rearwardly and inwardly extending parts 18 provide retaining means engaging within the groove between flange portions 11 and 12 and serve to hold the connector member fixed on the barrel. When in applied position the hypodermic needle extends through the closure member and axially beyond the forward syringe end.

Similarly in the structure shown in Figs. 5 6 and 7 a barrel 24 is furnished which at one end is provided with a piston or plunger 25 similar to plunger 13. This piston may also be furnished with a coupling element such as a screw threaded stem 26 for engagement with a correspondingly threaded actuator (not shown) by means of which it may be projected and retracted. The barrel 24 is flanged outwardly adjacent its opposite ends as at 27.

65 A closure member such as a rubber stopper 28 closes the forward end of the barrel bore and has its head portion overlapping surfaces of the adjacent flange 27 so that accidental inward shifting of this member is precluded. A connector member conveniently in the form of a cap 29 carries a double-ended needle 30. Both the barrel and cap 29 may be formed of material such that

they are capable of being indented; the indentations of barrel 24 having been indicated at 31 and the indentations of the cap skirt being indicated at 32. Especially the material of the cap will be such that it embodies resiliency.

Accordingly, the parts in their initial position may be arranged as shown in Fig. 5 in which the inner needle end has not perforated the diaphragm of the closure member. However, by exerting pressure in a direction axial of this cap with respect to the barrel, it will ride rearwardly over the same in telescoping relationship until the projections provided by indentations 32 enter into the recesses furnished by indentations 31 as shown in Fig. 7. In this manner the cap is prevented from being accidentally withdrawn or otherwise shifting over the outer end of the barrel. When the parts are in the positions shown in Fig. 7, any suitable form of actuator may be coupled with the plunger or piston 25. The latter may be shifted rearwardly to aspirate the syringe and also projected to cause an expulsion of medicament through the bore of the cannula.

Finally, as in Fig. 8, a barrel 33 may again be formed of any suitable material and have the rear end of its bore closed by a piston plunger 34. Its forward end is sealed by a closure 35 corresponding to closures 14 and 28. The opposite end edges of the barrel are flanged outwardly as at 36 to thus define in common with the structure of the preceding figures an external circumferential circular groove on the outer face of the barrel and extending through to the end portions of the same. Cap 37, again provided of any suitable material, mounts needle 38 and furnishes a connector member corresponding to caps 17 and 29. Thus, when it is shifted to the position indicated in dot and dash lines, its inner face will furnish a retaining surface engaging with the outer face of closure member 35. Its skirt will be retained against displacement with respect to the barrel by employing, for example, a ring 39 between the inner surface of this skirt and the outer face of the barrel. Obviously, as the parts are slid axially with respect to each other,

this ring engages within the groove on the outer barrel surface. As is apparent, the retaining ring is placed over the barrel and pressed into contact with the inner face of the skirt cap by using a suitable cement or other procedure calculated to prevent the detachment of the ring from the cap.

Thus, among others, the several objects of the invention as specifically aforementioned are achieved. Obviously numerous changes in construction and re-arrangements of the parts might be resorted to without departing from the spirit of the invention as defined by the claim.

I claim:

A syringe assembly including in combination a barrel, a closure at one end of said barrel, a plunger at the opposite end of the same, outwardly extending flanges forming a part of said barrel adjacent its ends, caps, an actuating stem slidably carried by one of said caps, a double-ended needle carried by the second of same, flanges in the form of spaced wing portions at diametrically opposite points in said caps and shiftable to positions overlying and engaging against said barrel flanges to retain said caps against movement with respect to said barrel.
